George C. Henrich
ATTORNEY-

UNITED STATES PATENT OFFICE

HEINRICH WIEFELSPÜTZ, OF BROOKLYN, NEW YORK, ASSIGNOR OF TWENTY-THREE AND ONE-THIRD PER CENT TO KARL WIEFELSPÜTZ, TWENTY-THREE AND ONE-THIRD PER CENT TO WILLIAM WIEFELSPÜTZ, OF BROOKLYN, NEW YORK, AND THIRTY PER CENT TO OTTO BECKER, OF NEW YORK, N. Y.

TOY

Application filed July 28, 1931. Serial No. 553,510.

This invention relates to improvements in toys, and it is the principal object of my invention to provide a toy in which by air blown into the toy, the representations of figures, such for instance a hen and a chicken arranged on the outside of a housing are imparted movements contributing greatly to the amusement of young and old.

Another object of my invention is the provision of a toy of this character in which the movements of the figures are produced by the inflation of a rubber bag or bag of inflatable material, acting against plates laterally arranged to the bag within a suitable casing and attached to rods, the upper ends of which are displaceable within slots of the casing, and extend through the same to the outside where they carry the figures.

Still another object of my invention is the provision of a toy equipped with a pipe stem through which the air for inflating the bag is blown, and in which a whistle or flute of any desired construction is arranged to accompany the movements of the figures by a musical tune or tunes in harmony with the respective representations.

A further object of my invention is the provision of a toy of this nature in which the rods carrying the figure operating plates are connected at their lower ends by elastic means to be tensioned upon the operation of the figures and upon their expansion during the exhaust of the air carrying the figures back into their normal positions after each operation.

A still further object of my invention is the provision of a toy of simple and inexpensive construction, yet durable and highly efficient in operation, the casing for which may have any desired shape, for instance egg-shaped if the representation of for instance a hen and chicken are used.

These and other objects and advantages of my invention will become more fully known as the description thereof proceeds, and will then be specifically defined in the appended claim.

In the accompanying drawings forming a material part of this disclosure:

Fig. 1 is a sectional front elevation of a

toy constructed according to my invention, the section being taken on line 1-1 of Figure 2.

Fig. 2 is a longitudinal section through the casing on line 2-2 of Figure 1.

Fig. 3 is a cross-section on line 3-3 of Figure 2 also showing the stem 13 in cross-section.

Fig. 4 is a detail view of an operating plate and co-operating parts.

Fig. 5 is a front elevation of a modified form of casing.

As illustrated, a casing 10 closed at its ends, as at 11 and 12, has formed with its wall a pipe stem 13 in which a whistle or flute 14 is arranged.

An inner lining 15 of the stem 13 is connected at its inner end within casing 10 with an inflatable bag 16 of suitable material for instance a rubber balloon or the like which, when air is blown through tube 15 to inflate the bag 16 will press against plates 17, 18, to which rods 19, 20 are attached, secured at their lower ends in casing 10 and extending with their upper ends through slots 21, 22, in the casing, preferably the upper wall thereof where they carry representations of figures such as for instance as shown a hen 23 and a chicken 24 attached at their rear to the flattened upper ends 25, 26, of the rods 19, 20.

The lower ends of bars or rods 19, 20, are connected within the casing or housing 10 by elastic means as for instance a spring 27.

In Figure 5, I have shown a modified form of casing in form of an egg 28 the construction of the device being otherwise the same as described above with respect to the preferred form of casing.

The device operates as follows:

Upon blowing air into stem 13 and its lining 15, the bag will be inflated and engage the plates 17, 18, to displace their rods 19, 20, laterally within the slots 21, 22, of the casing 10 to move the figures 24, 25, laterally apart.

Upon the interruption of the air supply the elastic connection 27 will draw the figures back into their original position, and a repeated blowing and exhaust of air in com-

paratively short intervals will move the figures to and fro in rapid succession so as to create to the onlooker's eyes the impression, if for instance the representations of a hen and her chick are used, that both are picking morsels of food from the ground, and if the flute in pipe stem 13 has an appropriate tune it will increase the illusion of picking fowl by its cluck-cluck tune.

- 10 It will be understood that I have described and shown the preferred form of my invention as one example only of the many possible ways to practically construct the same, and that I may make such changes therein as come within the scope of the appended claim without departure from the spirit of my invention and the principles involved, so for instance I can replace the representations of hen and chicken by representations of other animals and human beings, etc.

Having thus described my invention, what I claim as new and desire to secure by Letters Patent is:

25 A toy comprising a slotted casing, a stem formed therewith, an inner lining for said stem, a flute within said stem, an inflatable rubber balloon within said casing attached to said lining, a pair of plates adapted to be engaged by the inflated balloon to which said plates are attached, secured at their lower ends in said casing and extending with their upper flattened ends through the slots in said casing, the representation of a hen attached to the flattened end of one rod, the representation of a chicken attached to the flattened outer end of the other rod, and an elastic connection between the lower ends of said rods allowing the guiding of the representations apart during the inflation of the balloon and carrying the same back into their position close to one another after each operation, for creating the illusion of picking food upon the rapid inflation and deflation of said balloon.

- 45 Signed at New York in the county of New York, and State of New York, this 27th day of July, A.D. 1931.

HEINRICH WIEFELSPÜTZ.
